United States Patent Office

Des. 194,764
Patented Mar. 5, 1963

194,764

PRINTING PRESS

Donald A. Glaser, Emporia, and Jack E. Meeker, Merriam, Kans., assignors to Didde-Glaser, Inc., Emporia, Kans., a corporation of Kansas

Filed Oct. 19, 1961, Ser. No. 67,164

Term of patent 14 years

(Cl. D64—11)

Fig. 1.

Fig. 2.

Fig. 2.

Fig. 3.

Fig. 4.

Fig. 5.

Fig. 6.

FIG. 1 is a side perspective view of a printing press showing our new design;

FIG. 2 is a side elevational view thereof;

FIG. 3 is an elevational view of the side opposite to that shown in FIG. 2.

FIG. 4 is a top plan view thereof;

FIG. 5 is an end elevational view as seen from the left of FIG. 2;

FIG. 6 is an end elevational view as seen from the right of FIG. 2; and

FIG. 7 is a fragmentary, enlarged elevational view of the grill parts seen in FIGS. 1, 5 and 6.

The essential features of the design reside in the portions shown in solid lines.

We claim:

The ornamental design for a printing press, as shown and described.
